CROSSBOLT DEADLOCK

Russell W. Waldo, St. Paul, Minn., assignor to Ideal Security Hardware Corporation, St. Paul, Minn.

Filed Oct. 19, 1973, Ser. No. 407,789

Term of patent 14 years

Int. Cl. D8—07

U.S. Cl. D8—132

FIG. 1

FIG. 2

FIG. 3

FIG. 4

FIG. 5

FIG. 1 is a view in perspective of a crossbolt deadlock showing my new design;

FIG. 2 is a view in front elevation;

FIG. 3 is a view in end elevation as seen from the right to the left with respect to FIG. 2;

FIG. 4 is a bottom plan; and

FIG. 5 is a view in end elevation as seen from the left to the right with respect to FIG. 2.

I claim:

The ornamental design for a crossbolt deadlock, as shown.
